UNITED STATES PATENT OFFICE.

PERCY CLOUGH, OF KEIGHLEY, ENGLAND, ASSIGNOR OF ONE-HALF TO JOHN CLOUGH, OF SAME PLACE.

APPARATUS FOR FACILITATING DOFFING BOBBINS IN SPINNING.

SPECIFICATION forming part of Letters Patent No. 534,139, dated February 12, 1895.

Application filed September 8, 1894. Serial No. 522,487. (No model.)

To all whom it may concern:

Be it known that I, PERCY CLOUGH, spinner and manufacturer, a subject of the Queen of Great Britain, residing at Grove Mills, Keighley, in the county of York, England, have invented new and useful Improvements in Apparatus for Facilitating Doffing Bobbins in Spinning, Twisting, Doubling, and Similar Machinery, of which the following is a specification.

This invention is designed to facilitate the operation of doffing the filled bobbins and supplying their places with empty ones in spinning, twisting, doubling and similar machinery by substituting means mainly mechanical, and capable at once of actuating a whole side of a machine, for the present hand operation upon single bobbins, and to secure increase of speed, uniformity and economy in the operation.

Figures 1 and 1^a show by a side view part of a flier spinning frame having the invention applied. Fig. 2 shows by side view, partly in section, some of the parts in the position they occupy during spinning, drawn to a larger scale than Fig. 1. Fig. 3 shows by a like view to Fig. 2, the same parts in the position assumed when "doffing" takes place. Fig. 4 shows one of the flier stoppers by a front view. Fig. 5 shows by a side view the apparatus for lifting up the fliers, and the fingers by means of which the empty bobbins are supplied. Figs. 6 to 12 show details to be described. Fig. 13 shows by a part front view and Fig. 14 shows by a side view, the sliding support and attached parts. Figs. 15 and 16 show by front view and side view respectively an intermediate bracket. Fig. 17 shows by a sectional side view the gearing at the lower end of the spindles for winding and unwinding the fliers from the screw threads of the spindles. Fig. 18 shows the same by a front view, the worm wheels being shown out of gear and Fig. 19 shows a similar view but with the worm wheels in gear. Fig. 20 shows a detail to be described. Fig. 21 shows by a front view special apparatus for raising and lowering the lifter board when "doffing" is to take place.

50 The wire boards or guide boards *e* are hinged at *e'* and can all be turned up out of

the way at once as may be required during the operation of "doffing," by means of a flat bar *e*³, running the whole length of the wire boards which is hinged to the same bracket 55 *e*² as the wire boards. In the operation of the apparatus for performance of the "doffing" the fliers are all brought into line by suitable means such as follows:—On an axis *f* placed in bearings *f'* across the frame and 60 actuated by a handle at the end is a series of short arms or parts *f*² which lie out of the way until doffing is to be effected; when they are turned up each against one arm of a flier to prevent its rotation. See position shown 65 by broken lines Fig. 2.

At the lower part of each spindle *g* is provided a gear wheel *g'*, each of which at the proper time can be engaged by one of a series of worm wheels *g*², mounted on a horizontal shaft *g*³, carried by bearings from the framing and actuated from the end by a suitable handwheel *g*⁴ Fig. 1^a. The operation of the worm wheels *g*² is to unwind the spindles *g* from the screw threads of the fliers *g*⁵. 75 When the worm wheels *g*² have been pulled out of gear, see Fig. 18 a latch *g*⁶, bearing upon the collar *g*⁷, of the shaft *g*³, holds said worm wheels free from the gear wheels *g'*, and the same latch *g*⁶ serves to hold these 80 wheels in gear when moved into the position shown in Fig. 19.

The fliers *g*⁵ having been unscrewed the stoppers *f*² are turned away and the fliers, being free of the spindle screw threads, are 85 now engaged and lifted by a series of arms, *h*, *h'*, (Figs. 5 and 6) the upper arms *h* having holes *h*³ (see Fig. 12) for receiving the necks of the fliers, and the lower arms *h'* (see Fig. 11) being shaped to pass the spindle so as to 90 come underneath the shoulders of the fliers.

The upper arms *h* are carried by flat bars *h*⁸ extending along the front of the machine and supported on the axis *h*⁴ (Fig. 7) which rests upon bearings in brackets or sliding 95 supports *b* at the ends of and at suitable distances along the receptacle *b'*. Intermediate supporting brackets *d*, Fig. 5 are also placed at suitable distances apart along the sliding receptacle *b'*. The axis of the bar *h*³ also carries bearings *h*⁷ for the axis *h*⁹ of another flat bar *h*⁵ which carries the lower arms *h'*. The

bar h^5 can partly rotate on its axis h^6 . The bars h^3, h^5 are provided with handles h^8, h^9 respectively at one end of the machine to enable the arms h, h' being turned as required 5 the positions being maintained by suitable catches $h^{10} h^{11}$.

In front of the frame suitably supported on vertical guides a , are supports b for a receptacle b' for the filled bobbins, and this support, with the receptacle, is raised and lowered by suitable chains b^2 passing over pulleys b^3 upon a rotatory shaft b^4 , carried by suitable arms A from the framing A' . At one end of the frame, the shaft b^4 has mounted on it a worm wheel c which engages with the worm c' upon the spindle c^2 carried by the member c^3 upon the arm A . At the lower end of the spindle c^2 is provided beveled gear wheels c^4, c^5 operated by hand wheel c^6 mounted on the framing. By these means the chains b^2 may be wound upon or unwound from the pulleys b^3 , thus raising or lowering the receptacle b' with its attached parts.

The supports b are provided with antifriction rollers b^5, b^6 , bearing upon the vertical guides a . The length of the chains b^2 may be adjusted by means of suitable bolts b^6 and nuts b^7 .

The receptacle b' for the filled bobbins carries a blade or part b^8 having a series of notches or slits into which the thread or yarn is laid by the fall of its bobbin into the receptacle. Adjacent to this part b^8 is another strip or blade b^9 provided with a series of cutters b^{10}, b^{11} , and having a handle b^{11} at one end of the receptacle, the whole series of threads across the frame being simultaneously severed thereby. The movement of the blade b^9 is controlled by suitable stops, and anti-friction rollers b^{12} are provided at suitable distances apart, see Fig. 14 the handle b^{11} being removed in this figure for the sake of clearness.

The lifter plate or bar i is caused to traverse by the ordinary means during spinning but for doffing is carried high by means of special apparatus, shown in Fig. 21. A rotat- 45 ing axis j^3 is provided and is operated by a hand wheel j^4 at the end of the machine as shown in Fig. 1. Upon the axis j^3 is a pulley j^2 operating a chain or band j' passing around a guiding pulley j^7 carried by a support j^8 from the framing A' . The lower end of this chain j' is connected to the ordinary sliding bar j^9 by lugs j^{10} . The sliding motion given to the bar j^9 by these parts is transmitted to the lifter bar i in the usual way, when the apparatus commonly known as Scaife's lifter motion is employed. A pulley mounted on 55 the same axis j^3 carries a counter weight for balanceing the weight of the lifter bar, &c., and a ratchet wheel j^5 and catches or pawls j^6 (see Fig. 1) serve to hold the parts in position.

For knocking off the full bobbins a flat bar 60 k is hinged at suitable intervals to the bar e^8 which lifts all the wire boards at once. When the wire boards are turned up and the

full bobbins have been lifted to a suitable height up the spindles, the bar k is swung forward on its hinges k' and strikes all the 70 full bobbins off the lifter bar i into the receptacle. The fresh supply of empty bobbins to replace these full bobbins is arranged (as shown by dotted lines Fig. 5) upon a series of fingers d' carried by flat bars d^2 along the 75 front of the spinning frame. These bars are provided at suitable distances with axes d^3 , see also Fig. 10, which are carried by bearings in the supports b and d from the sliding receptacle b' . At the appropriate time these 80 fingers are overturned, by means of a handle d^4 , Figs. 1 and 13 into the full line position Fig. 5 thereby capsizing the empty bobbins onto the ends of the spindles.

When a series of bobbins have become full 85 the operation of "doffing" may be performed as follows: The machine having been stopped, the sliding support b with its attached parts, is lowered by the means described until the pointer or finger a' reaches a suitably marked 90 position which may be indicated on the vertical guides a by the word "Doff." This brings the flier lifters h, h' between the front rollers and the tops of the spindles. The knife b^9 is then pulled out and the wire boards 95 e are raised by a handle at one end of the frame. The flier stoppers or parts f^2 are raised up against the fliers, and the worm wheels g^2 pushed into gear which being turned in the direction opposite to spinning, cause 100 the fliers to be unscrewed free of the screw threads of the spindles. The flier stoppers f^2 may be lowered again. The axis carrying upper arms is then turned into such position that the holes h^2 are exactly above the tops 105 of the fliers. The receptacle is then lowered until the boss of flier enters the hole in the upper arm. The axis carrying lower arms is now turned by means of its handle h^9 bringing up these lower arms into position underneath the shoulders of fliers thereby clasping fliers between top and bottom arms as shown in Fig. 5. The sliding motion is reversed and the parts lifted carrying the fliers to a height at which the full bobbin can come 115 off and the empty bobbin go on in its place. At the same time as these parts are raised the lifter plate with full bobbins is raised, until said bobbins are nearly clear of the spindles, by means of the hand wheels j^4 and apparatus described with respect to Fig. 21. The bobbins are then knocked over in the manner already described. The lifter plate is then lowered and the fingers carrying the empty bobbins are overturned so that the bobbins 125 slide down on to the spindles. The fingers are then returned to the dotted position Fig. 5. The receptacle b and its attachments are then lowered until the fliers are on to the tops of the spindles when the lower arm h' is released by turning it downward. Then the receptacle is raised until the upper arm h is sufficiently clear of the fliers to allow it to be turned down out of the way. After lowering 130

the wire boards, the fliers are screwed on to the spindles by the latter being turned in the direction of spinning by means of the worm wheels g^2 which at the same time wind upon 5 the empty bobbins a few turns of yarn or thread. The severance of the threads then takes place the worm wheels are pulled out of gear, the receptacle b' and its attachments are taken up out of the way and the machine 10 is restarted. By these means I avoid taking up the space of the frame near the ordinary running parts of the frame.

The receptacle for full bobbins which rises and falls with the other parts referred to, is 15 only allowed to remain down while it is actually in use it going up out of the way, by the gearing being operated as at other times.

Having now particularly described and ascertained the nature of my said invention and 20 in what manner the same is to be performed, I declare that what I claim is—

1. The combination with the framing A' and bracket e^2 , of the guide boards e and flat bar e^3 hinged to said bracket, and the bar k 25 hinged to the bar e^3 , whereby the guide boards may all be turned up out of the way at once and the bar k be swung forward on its hinges, to strike all the full bobbins off from a lifter bar and into a receptacle, substantially as described.

2. The combination of the vertically movable receptacle b' , the lifter bar i , the hinged and upwardly turning guide boards e , the hinged bar e^3 movable with said guide boards, 35 and the bar k hinged to the bar e^3 and adapted to be swung forward to strike the free bobbins off from the lifter bar and into the receptacle, substantially as described.

3. The combination of the axis f provided 40 with a handle and having a series of stopper arms f^2 that are normally out of the way un-

til doffing is to be effected, the fliers g^5 , the spindles g each having at its upper end a screw threaded connection with a flier and provided at its lower end with a gear g^6 , the 45 shaft g^8 actuated by hand wheel g^4 and provided with worm wheels g^2 adapted to be engaged with and disengaged from the gears on said spindles, and a latch g^6 adapted to engage a collar g^7 on the shaft g^3 to lock the worm 50 wheels in gear with or free from the gears on the spindles, substantially as described.

4. The combination with the fliers g^5 , of the series of arms h and h' , the upper arms h being provided with holes h^2 to receive the 55 necks of the fliers and the lower arms h' being adapted to pass around the spindles and engage beneath the shoulders of the fliers, the bars h^3 , h^5 from which said upper and lower arms are supported and provided with 60 handles h^8 , h^9 by which the said arms may be turned, and vertically sliding supports for said bars, substantially as described.

5. The combination of the vertically movable receptacle b' provided with means for 65 holding and severing the threads or yarn, the lifter plate or bar i and its operating mechanism, the knocking off bar k and the hinged guide boards e , substantially as described.

6. The combination with the vertically 70 sliding receptacle b' and its supports b , d , of the flat bars d^2 provided with series of fingers d' and the handle d^4 for overturning said fingers, substantially as described.

In testimony whereof I, the said PERCY 75 CLOUGH, have hereunto set my hand this 23d day of August, 1894.

PERCY CLOUGH.

Witnesses:
